UNITED STATES PATENT OFFICE

2,453,537

TUBE-FORMING MACHINE

Edwin R. Phillips, Evanston, Ill., assignor to Morton Salt Company, Chicago, Ill., a corporation of Illinois

Application April 12, 1946, Serial No. 661,776

9 Claims. (Cl. 93—80)

1

The invention relates generally to a machine for forming paper tubes and more particularly to a machine for continuously forming paper tubes by wrapping strips of paper on a rotating mandrel.

Machines of the general type above described have long been satisfactorily employed for the forming of cylindrical tubes, the formation of such tubes on rotating mandrels presenting very few problems because of the uniform distances, and hence speeds, of all surfaces of the rotating mandrel, and the tube being formed thereon, from the center of the mandrel. The formation of noncylindrical tubes in this manner has, however, presented many problems some of which are still not satisfactorily overcome even though there are on the market machines designed to form tubes having a plurality of straight sides.

It is a general object of the invention, therefore, to provide a new and improved machine for forming noncylindrical paper tubes on a rotating mandrel.

A more particular object is to provide a machine for forming noncylindrical paper tubes by the winding of strips of paper on a rotating mandrel in which the mandrel may be rotated continuously and at a higher speed than that of present machines while, at the same time the strips are caused to conform precisely to the mandrel to result in a concisely and accurately formed tube.

Another object of the invention is to provide a tube-forming machine in which the strips of paper compiled to form the tube are caused closely to hug and to conform to the mandrel by fluid pressure acting on the strips of paper as it is wound on the mandrel.

Still another object is to provide a tube-forming machine having a rotatable mandrel upon which the strips of paper are wound to form the tube and a cylindrical casing surrounding the mandrel over a length thereof including the point of application of the strips of paper to the mandrel, and jets carried by the casing directed radially inwardly against the mandrel and discharging fluid under high pressure for impinging against the strips of paper.

Other objects and advantages will become apparent from the following detailed description taken in connection with the accompanying drawings, in which:

Fig. 1 is a fragmentary view primarily in elevation but partially in section of a tube forming machine embodying the features of my invention.

Fig. 2 is a partial, transverse sectional view

2

taken approximately along the line 2—2 of Fig. 1.

Fig. 3 is a transverse sectional view taken approximately along the line 3—3 of Fig. 1.

Fig. 4 is a transverse sectional view taken approximately along the line 4—4 of Fig. 1.

While the invention is susceptible of various modifications and alternative constructions, it is here shown in the drawings and will hereinafter be described in a preferred embodiment. It is not intended, however, that the invention is to be limited thereby to the specific construction disclosed. On the contrary, it is intended to cover all modifications and alternative constructions falling within the spirit and scope of the invention as defined in the appended claims.

As shown in the drawings for purposes of disclosure, the machine comprises generally a bed or base 10 having upstanding from one end thereof, herein the right end as viewed in Fig. 1, a column 11. Extending longitudinally of the bed 10 is a mandrel, generally designated 12, which at its right hand end, as viewed in Fig. 1, has a reduced cylindrical portion 13 which is journaled in the column 11. The remaining portion 14 of the mandrel is herein shown as rectangular, though it is to be understood that the portion 14 of the mandrel may take any other shape including cylindrical, though the invention is primarily concerned with the formation of noncylindrical tubes. The noncylindrical portion 14 of the mandrel is hollow (Fig. 2) but is closed at the end remote from the reduced portion 13.

At the left hand end, as viewed in Fig. 1, the mandrel 12 is engaged by means, generally designated 15, serving as a support for that end of the mandrel, driving means for the mandrel and means for stripping the formed tube from the mandrel. This means comprises a drum 16 having at each end a radially outwardly extending flange 17. These flanges are received in grooved rollers 18 mounted on the bed 10 so as rotatably to support the drum 16 while at the same time retaining the drum against axial movement. Intermediate the flanges 17, the drum is formed with a somewhat reduced surface 19 forming a pulley for the reception of a drive belt 20 which extends to any suitable power source such as an electric motor (not here shown). Extending inwardly, as best seen in Fig. 4, are pairs of brackets 21. Rotatably supported in each pair of brackets is a roller 22 and, inasmuch as it is desirable to have a roller engage each face of the mandrel 12, the pairs of brackets and the number of rollers will correspond to the number of faces on the mandrel. The mandrel 12, herein shown being

rectangular, there are four rollers 22. As will readily be understood, the rollers as a whole rotate with the drum 16 so as to serve as a support and as a driving means for the mandrel.

In order that the rollers 22 may also serve as a means for stripping the formed tube off of the mandrel, means is provided for rotating each roller 22 about its axis. To that end each roller is keyed to a shaft 23 extending axially thereof and in turn rotatably journaled in the pairs of brackets 21. At one end each shaft 23 projects through a bracket 21 and at that end carries non-rotatably fixed thereon a bevel gear 24. Each bevel gear 24 in turn meshes with a bevel gear 25 fast on a shaft 26 extending generally parallel with the mandrel 12 and rotatably supported in yoke-like brackets 27 also formed integral with the drum 16. At the end remote from the bevel gear 25, each shaft 26 has fast thereon a spur gear 28. The spur gears 28 in turn mesh with an internally toothed ring gear 29 which is non-rotatably supported on the bed 10 coaxially with the mandrel 12 and the drum 16. It will be readily understood that as the drum is rotated it will, of course, carry with it the rollers 22 and thus, through the rollers, will impart rotation to the mandrel 12. At the same time, this rotation of the drum will through the action of the stationary ring gear 29 and the geared connection of the rollers 22 therewith rotate the rollers. The direction of rotation of the drum will, of course, be such that the rollers 22 rotate in a direction to feed the formed tube off of the free end, herein the left hand end, of the mandrel 12.

Tubes of the character here in question are composed of several plies or layers of paper strips 30 gummed to adhere and overlap so that one layer covers the joint formed between the strips of an adjacent layer. The strips of paper 30 are, in well known manner and as seen in Fig. 1, applied to lie diagonally of the faces of the mandrel and are maintained under a desired tension. Inasmuch as the means for gluing and positioning the strips of paper and for maintaining them under desired tension are all common and well known and form no feature of this invention, they are not here shown.

As above indicated, difficulties are experienced in forming noncylindrical tubing on a continuously rotating mandrel and, while machines have been designed for forming noncylindrical tubing, they are either of a highly complicated character or operate at a very low production rate, or are otherwise not the final, complete solution to this problem. It is a feature of this invention to provide a simple yet expedient means for making possible formation of a noncylindrical tube on a rapidly revolving mandrel. This means herein takes the form of a cylinder 31 disposed in concentric relationship to the mandrel 12 intermediate the column 11 and the drum 16. The cylinder 31 is of a minimum diameter which will still permit rotation of the rectangular portion 14 of the mandrel therein and is of a length to extend from a point adjacent the drum 16 toward the column 11 beyond the point of application of the strips 30 to the mandrel. One of the functions of the cylinder 31 is to provide a support for means that serve to produce a constant but yieldable force urging the strips 30 to conform to the contour of the mandrel. This force takes the form of jets which are directed inwardly against the mandrel and thus impinge against the strips 30 being wound on the mandrel. To the end of creating this constant but yieldable force which

travels without friction over the strips as the mandrel is rotated, the cylinder 31 is made with an outer wall 32 and an inner wall 33 so as to form therebetween an annular chamber 34. Opening to the chamber 34 through the outer wall 32 is a conduit 35 for supplying suitable fluid under pressure from a source not here shown. Normally it is contemplated that this fluid will be air, though it is conceivable that other fluid may prove usable and more desirable. Mounted in the inner wall 33 are a plurality of radially inwardly directed nozzles 36 through which the fluid in the chamber 34 is discharged to form the jets above described. Each of the nozzles 36 preferably is somewhat elongated and disposed with its longitudinal dimension longitudinally of the cylinder so as to discharge an elongated rather than a more nearly circular jet. By way of illustration, it being understood that the arrangement may be varied to suit different conditions, a majority of the nozzles 36 are herein shown arranged in four longitudinal rows disposed respectively in the vertical and the horizontal diametrical planes of the cylinder. Of these rows of nozzles the top row 20 extends from near the left hand end of the cylinder to the extreme right hand end, while the other rows may terminate one or two nozzles short of the right hand end of the cylinder depending somewhat on the pitch, that is, angle, of the strips 30 being wound on the mandrel.

Additional nozzles are provided and so located as to assure the impingement of one or more jets on the strips at and in advance of the point of application of the strips to the mandrel, that being the critical point in the formation of the tube. Among the difficulties experienced in the past when a continuously and rapidly rotating non-cylindrical mandrel is employed is that of getting the strips 30 to lie flat against the sides of the mandrel. The whip given to the strips as they are pulled at different speeds because of the difference in radius of various portions of the mandrel and the centrifugal force tends to cause the strips to bulge radially outwardly preventing their proper adherence to the adjacent inner layer or tier and tends to cause improper point contact. The result of such whipping and improper advance point contact is, of course excess material for the side of the tube resulting in a wrinkle or fold when the strips 30 are eventually conformed precisely to the mandrel. Accordingly, a plurality of additional nozzles 37 (see Fig. 2) are provided at the right hand end of the cylinder 31 and in such position circumferentially 40 of the cylinder as to impinge against the strips 30 prior to or at the point or time of engagement of the strips with the mandrel. Herein a single row of such additional nozzles 37 is shown. It is to be understood that additional rows may be employed if it proves desirable or necessary. This row of nozzles is spaced approximately 45° in a clockwise direction, as viewed in Fig. 2, from the top row of nozzles in view of the fact that the strips 30 are herein fed into the cylinder at a point approximately 25° in a counterclockwise direction from the top row of nozzles, the cylinder at that point being formed with a narrow, elongated slot 38. The upper edge 39 of the slot is curved to form a smooth guide for the strips of paper 30.

As will readily be seen from the drawings, particularly Fig. 2, the jets from the top row of nozzles 36 and from the nozzles 37 impinge against the strips 30 prior to the contact thereof with the mandrel and thus tend to bow the strips in-

wardly, overcoming any outward whip that might be given to the strips. The strips thus are at all times urged toward the flat surfaces and thereby the contact of the strips with the mandrel is a progressive one and not a skip point contact resulting in an excessive length of strip for a given side of the mandrel. The other jets come into play after the strips have made contact with the mandrel and retain the strips tightly against the sides of the mandrel continuously from the time that the strips are first applied, and when the adhesive thus has not yet had an opportunity to set, until the adhesive has set and the tube has taken a definite form.

While it is believed that the jets will retain the strips in close conformity with the mandrel, the cylinder 31 is provided with end closures 41 and 42 so as to make of the cylinder 31 a pressure chamber. The end closure 41 may conveniently be supported on longitudinal extensions 43 of the brackets 21 and thus rotate with the drum 16 and with the mandrel 12. The closure 42 may be supported directly from the mandrel 12. The closure 42 may, of course, have an air tight fit with the mandrel 12 while the closure 41 will have to be spaced from the mandrel a sufficient distance to permit passage of the formed tube therethrough. It is, however, not essential that the cylinder be completely air-tight. As a matter of fact, it is imperative that there be some provision for the escape of fluid from the cylinder because there is a constant supply of fluid to the cylinder through the nozzles 36 and 37. Thus the end closures need serve only to cause the building up of pressure within the cylinder and need not seal the cylinder.

To enhance the effectiveness of the pressure built up within the cylinder 31, the mandrel 12 may over a portion of its length be formed with radial apertures 44 and the cylindrical portion 13 of the mandrel formed with an axial passage 45 adapted through a conduit 46 to be connected to a vacuum or suction pump (not here shown). In this way, a pressure differential may be established and thus further aid in retaining the strips conforming precisely to the shape of the mandrel. The radial apertures 44 preferably are formed in the mandrel only over that length of the mandrel within the cylinder 31 that is for the most part covered by strips 30. The extent of pressure differential should not be too great because of the difficulty which would then be encountered in stripping the formed tube off of the mandrel.

It will be apparent therefore that I have perfected a means for readily and conveniently providing a yieldable yet ever-present force or pressure urging the strips 30 against the flat sides of the noncylindrical mandrel and that, in particular, I have provided means for urging the strips into contact with the flat sides of the mandrel in advance of the time when they would normally make that contact under the influence of the mandrel alone. As a matter of fact, with my construction a progressive contact of the strips with the surfaces of the mandrel is effected assuring a close conformity of the strips to the mandrel. By this progressive contact of the strips with the mandrel, there is eliminated the bulging of the strips or other irregularities that may be formed as a result of a corner of the 70 mandrel making contact with the strips before contact of the mid portion of a face of the mandrel makes contact with the strips.

I claim as my invention:

1. In a paper-tube-forming machine, a rotata-

ble mandrel upon which strips of paper are wound to form the tube, means for rotating said mandrel and for continuously stripping from said mandrel off of a free end thereof the formed tube, and means for directing a stream of fluid against the strips both before and after application to said mandrel to urge the strips radially inwardly toward engagement with the mandrel.

2. In a paper-tube-forming machine, a rotatable mandrel upon which strips of paper are wound to form the tube, means for rotating said mandrel and for continuously stripping from said mandrel off of a free end thereof the formed tube, a plurality of rows of nozzles extending longitudinally of said mandrel in spaced relation thereto and directed radially inwardly against said mandrel, and means for supplying fluid under pressure to said nozzles.

3. In a paper-tube-forming machine, a rotatable mandrel having a noncylindrical portion upon which strips of paper are wound to form the tube, means for rotating said mandrel and for continuously stripping the formed tube off of a free end of said mandrel, and means for directing a stream of fluid against the outside of the inside of said strips of paper to cause progressive contact of the strips with said mandrel.

4. In a paper-tube-forming machine, a rotatable mandrel having a noncylindrical portion upon which strips of paper are wound to form the tube, means for rotating said mandrel and for continuously stripping the formed tube off of a free end of said mandrel, a plurality of rows of nozzles extending longitudinally of and directed radially inwardly of said mandrel and positioned in circumferentially spaced relationship to be disposed on all sides of said mandrel, and means for supplying fluid under pressure to said nozzles for discharging therefrom in impinging relationship against the strips.

5. In a paper-tube-forming machine, a rotatable mandrel having a noncylindrical portion upon which strips of paper are wound to form the tube, means for rotating said mandrel and for continuously stripping the formed tube off of a free end of said mandrel, a plurality of rows of radially inwardly directed nozzles extending longitudinally of said mandrel and positioned in circumferentially spaced relationship to be disposed on all sides of said mandrel, an auxiliary row of nozzles also extending generally longitudinally of said mandrel and spaced a short peripheral distance in the direction of rotation of said mandrel from a perpendicular to the axis of said mandrel, and means for discharging fluid under pressure through said nozzles.

6. In a paper-tube-forming machine, a rotatable mandrel having a noncylindrical portion upon which strips of paper are wound to form the tube, means for rotating said mandrel and for continuously stripping the formed tube off of a free end of said mandrel, a plurality of rows of nozzles extending longitudinally of said mandrel, said rows of nozzles being uniformly spaced circumferentially about said mandrel with one row of nozzles positioned just slightly in the direction of rotation of said mandrel from the intersection of the strips with a circle passing through the rows of nozzles, an auxiliary row of nozzles spaced a further distance in the direction of rotation of said mandrel from the point of intersection of the strips and the circle passing through said rows of nozzles, and means for supplying fluid under pressure to said nozzles for impinging against the strips wound on said man-

drel and forcing the strips to lie flat on the mandrel.

7. In a paper-tube-forming machine, a rotatable mandrel having a noncylindrical portion upon which strips of paper are wound to form the tube, means for rotating said mandrel and for continuously stripping the formed tube off of a free end of said mandrel, a cylinder surrounding said mandrel at the point of application of strips to said mandrel and extending in opposite directions from that point, said cylinder being double-walled to form an annular chamber, a plurality of rows of nozzles extending longitudinally of said cylinder and opening through the inner wall thereof to communicate with the annular chamber, said rows of nozzles being uniformly spaced circumferentially of said cylinder, a slot in said cylinder through which the strips of paper are fed to said mandrel, said slot being positioned slightly behind one row of nozzles considered in the direction of rotation of said mandrel and an auxiliary row of nozzles carried by said cylinder somewhat in advance of said last identified row of nozzles, and means for supplying fluid under pressure to said annular chamber for discharge as radially inwardly directed jets impinging on the strips of paper both prior and subsequent to contact of the strips with said mandrel.

8. In a paper-tube-forming machine a rotatable mandrel a noncylindrical portion upon which strips of paper are wound to form the tube, means for continuously rotating said mandrel and for continuously stripping the formed tube off of a free end of said mandrel, means forming a pressure chamber surrounding said mandrel at

the point of application of the strips of paper thereto and for a distance in the direction of extension of the tube being formed, and a plurality of nozzles for discharging fluid in the form of jets positioned to impinge on the strip of paper prior to contact thereof with the mandrel.

5 9. In a paper-tube-forming machine a hollow rotatable mandrel having a noncylindrical portion upon which strips of paper are wound to form the tube, means for continuously rotating said 10 mandrel and for continuously stripping the formed tube off of a free end of said mandrel, means forming a pressure chamber surrounding said mandrel at the point of application of the strips of paper thereto and for a distance in the 15 direction of extension of the tube being formed, a plurality of nozzles disposed within said chamber forming means directed radially inwardly for the discharge therefrom of jets impinging upon the strip wound on said mandrel both before and 20 after contact of the strip with the mandrel, said mandrel having apertures formed therein in the portion disposed within said pressure chamber forming means, and means for creating a vacuum in the mandrel.
